UNITED STATES PATENT OFFICE

HARRY J. WAIN, OF NEW BRIGHTON, PENNSYLVANIA, ASSIGNOR TO MAYER CHINA COMPANY, OF BEAVER FALLS, PENNSYLVANIA, A CORPORATION OF PENNSYLVANIA

DESIGN FOR A PLATE OR SIMILAR ARTICLE

Application filed July 12, 1932. Serial No. 44,315. Term of patent 14 years.

To all whom it may concern:

Be it known that I, HARRY J. WAIN, a citizen of the United States, residing at New Brighton, in the county of Beaver and State of Pennsylvania, have invented a new, original, and ornamental Design for a Plate or Similar Article, of which the following is a specification, reference being had to the accompanying drawing, forming part thereof.

In the drawing:

The figure is a face view of the plate, partly broken away, showing my new design, in which the detail border line illustrated extends entirely around the circumference.

I claim:

The ornamental design for a plate or similar article, as shown and described.

HARRY J. WAIN.
